Primary Examiner—Joel Sincavage*Assistant Examiner*—Elizabeth Albert(74) *Attorney, Agent, or Firm*—Fitch, Even, Tabin & Flannery**CLAIM**

We claim the ornamental design for a drop wire clamp, as shown and described.

DESCRIPTION

FIG. 1 is a perspective view of a drop wire clamp according to our new design, the broken lines of which are for illustrative purposes only and form no part of the claimed design; and,

FIG. 2 is a side elevational view of the drop wire clamp of FIG. 1.
